2 SHEETS—SHEET 2.

UNITED STATES PATENT OFFICE.

JOHN F. CAWL, OF BUFFALO, NEW YORK.

SLIDING-DOOR FASTENER.

1,216,286.

Specification of Letters Patent. Patented Feb. 20, 1917.

Application filed June 13, 1916. Serial No. 103,420.

To all whom it may concern:

Be it known that I, JOHN F. CAWL, a citizen of the United States of America, residing at Buffalo, county of Erie, and State of New York, have invented certain new and useful Improvements in Sliding-Door Fasteners, of which the following is a full, clear, and exact description.

My invention relates generally to sliding doors and more particularly to freight car doors and locking means therefor.

It is well known, to those skilled in the art, that freight car doors which are hung on the outside of the car often become derailed or otherwise dislocated, and frequently are torn from the car by passing trains. Furthermore, with the present construction of doors there is no way of effectively locking the same.

One of the objects of my invention has been to provide a sliding door for freight cars which shall be mounted to operate within the casing of the car, thereby making it impossible for the door to be accidentally dislodged or detached.

Another object has been to provide a novel and effective locking means for the door, which cannot be operated by any unauthorized persons.

Furthermore, I have sought to provide a lock for my door, which, when set in its open position, shall remain so set until the door is partly open, and be re-set by further movement of the door.

Moreover, my invention is simple and cheap to manufacture, of few parts, and durable in its construction.

The above objects and advantages have been accomplished by the device shown in the accompanying drawings. In the drawings forming part of this application:

Figure 1 is a sectional elevation of the frame work of the freight car, taken on line 1-1 of Fig. 2, showing my complete device in side elevation.

Fig. 2 is a fragmentary, sectional, plan view, taken on line 2-2 of Fig. 1.

Fig. 3 is a fragmentary elevation of the device shown in Fig. 1 and shows the parts of the lock in their open positions.

Fig. 4 is a fragmentary, sectional elevation through a car provided with my device and is taken on line 4-4 of Fig. 3.

Fig. 5 is a fragmentary, sectional, plan view of a portion of the lock of my device and is taken on line 5-5 of Fig. 1.

Fig. 6 is a similar view with the parts thereof in the positions in which the lock may be opened.

Fig. 7 is a fragmentary, rear view of the lock casing and shows the stud key in its locked position.

Fig. 8 is a similar view showing the stud key in its released position.

Fig. 9 is a perspective view of the operating key.

In the drawings: 15 represents a box car to which my device is attached showing the door and locking means thereof arranged within the casing 16 of the car. 17 is the door of my device which is made, preferably, of sheet metal, and has secured along its upper edge two angle irons 19, whereby it is stiffened and strengthened. These angle irons also form a support for the rollers 18. 75 The rollers 18 are supported by tracks 20, formed preferably of angle iron, and suitably supported within the casing 16 of the freight car. The door 17 is provided near its front edge with an aperture 69 and the door is so arranged that it will move into the casing flush with the edge of the opening in the car.

The door of my device is provided at its front end, in the upper and lower edge, 85 with a notch 25. 26 is an upper lock lever and 27 is a lower lock lever. These levers are each provided at their outer edge with hooks 67 which are arranged to engage with the notches 25 in the door. The upper 90 lock lever 26 is pivotally secured to a bracket 68, carried by the outwardly extending ends of the tracks 20. The lower lock lever 27 is set into the casing of the car and is pivotally secured by a bracket 28 suitably carried by the frame work of the car.

29 is the lock casing of my device which is located within the frame work of the car and at some point adjacent the opening in the car at the front edge of the door. Within this casing is rotatably mounted a lock member 30 (Figs. 5 and 6), which is provided with a central, annular portion 31, and radial arms 32 and 33 arranged diametrically opposite each other. The upper 105 lock lever 26 is connected with the arm 33 by means of a link 34 and the lower lock lever 27 is connected with the arm 32 by means of a link 35, whereby the outer ends of the lock levers will be moved toward or from each other by the rotation of the lock member 30. A helical spring 53 is connected

at one end to the outer end of the arm 33 and at its other end to the casing 29, whereby the lock member 30 and lock levers 26 and 27 are kept normally in the positions shown in Fig. 1.

The lock member 30 is provided in its forward portion with a central aperture 36 and at its inner end with a reduced aperture 37, thus forming a shoulder 38. A lock stud 39, 10 is slidably disposed within the aperture 37 and is provided with a head 40, arranged within the aperture 36. The inner end of the bearing stud is provided with a stud key 41 which extends diametrically across the 15 end of the stud and is engageable with a slot 42 formed in the inner end of the lock member 30 and in a bearing plate 43, whereby the stud member 30 and stud are locked against rotation when said key is in engagement with said slot. A pin 44 is arranged 20 in the lock member 30 and passes through an enlarged slot 45 formed in the lock stud, whereby the axial movement of said stud is limited. A helical spring 46 is disposed 25 within the aperture 36 of the lock member and between the shoulder 38 and head 40 of the lock stud, whereby the lock stud is retained normally in the position shown in Figs. 5 and 7.

30 47 is the operating key of my lock, which has a round shank 48 and a T-shaped handle 49. The shank 48 of the key is provided with two diametrically opposite and radially extending lugs 51 which are arranged 35 to engage with slots 52 formed in the wall of the outer end of the lock member 30. These lugs are so located that before they come into engagement with the slots 52 the lock stud 24 has been pushed inwardly by 40 the shank 48, sufficiently far to release the stud key 41 from engagement with the slot 42.

Arranged on the upper edge of the door and near its forward end is a trip block 54 45 which is engageable with the outer end of a trip lever 56, pivotally supported by a suitable bracket 57. Within the casing 29 of the lock is arranged a trip arm 58 which is pivotally supported at one end and connected at 50 its other end to the outer end of the trip lever 56 by means of a link 59. This arm is provided with a detent 60 which is engageable with a notch 61 formed in the periphery of the annular portion 31 of the lock member 30. A helical spring 62 is arranged within the casing 29 and is connected to the lock arm 58, whereby the detent 60 is kept 55 normally in contact with the annular part 31 of the lock member.

60 When the door of my device is closed and locked the parts are in the positions shown in Fig. 1. When it is desired to open the door the operating key 47 is placed within the aperture 36 of the lock member and, 65 when the lugs 51 are in register with the

slots 52 of the said lock member, the key is pushed inwardly so as to move the lock stud 39 axially and release the stud key 41 from its engaging slot 52 (Fig. 6). This releases the lock member 30 which may then be rotated by the operating key. When the lock member is rotated to the position shown in Fig. 3 the lock arms 26 and 27 will have their outer ends released from the notches 25 of the door and at this time the detent 60 70 will engage with the slot 61 of the lock member and thus prevent the return of the lock member to its normal position. When this detent is in the position shown in Fig. 2 the trip arm 58 will be slightly raised and the outer end 55 of the trip lever 56 will be lowered so as to be in the path of travel of the trip block 54. The door may now be opened and when the trip block 54 engages with the outer end 55 of the trip lever this 75 end of the lever will be raised, and, through the medium of the link 59, will operate the trip arm 58 so as to release the detent 60 from engagement with the notch 61 of the lock member. The lock member, together 80 with the parts connected therewith, will now be moved, by the helical spring 53, to their normal positions (see Fig. 1) whereby the lock levers will be reset and in position to again engage with the notches 25 of the door 85 when it is closed.

Obviously, some modifications of the details herein shown and described may be made without departing from the spirit of my invention or the scope of the appended 90 claims, and I do not, therefore, wish to be limited to the exact embodiment herein shown and described.

Having thus described my invention, what I claim is:

1. In a construction of the character set forth, the combination with a door casing, of a door slidably mounted within said casing, said door being formed with a notch in the upper and in the lower edge, pivotally 100 mounted lock levers, within said casing, engaging each of the notches in said door, and lock-controlling means, within said casing, governing the positions and operation of said levers.

2. In a construction of the character set forth, the combination with a door casing, of a door slidably mounted within said casing, said door being formed with a notch in the upper and in the lower edge, pivotally 110 mounted lock levers, within said casing, engaging each of the notches in said door, lock-controlling means, within said casing, connected with said lock levers, a trip lever pivotally mounted within said casing and 115 near one of said lock levers, means for keeping said lock levers in their open positions, and means carried by said door and engageable with said trip lever for resetting said lock levers.

3. In a construction of the character set forth, the combination with a door casing, of a door slidably mounted within said casing, said door being formed with a notch in the upper and in the lower edge, pivotally mounted lock levers, within said casing, engaging each of the notches in said door, lock-controlling means, within said casing, connected with said lock levers, said lock-controlling means comprising, a lock lever formed with a central aperture in its forward end and a reduced aperture in its rear end, a lock stud slidably mounted within the apertures, a stud key for preventing the

rotation of said lock member, and an operating key engageable with the aperture in the forward end of said lock member, whereby said lock member is released when said operating key is inserted in the last mentioned aperture. 15

In testimony whereof, I have hereunto signed my name in the presence of two subscribing witnesses.

JOHN F. CAWL
